UNITED STATES PATENT OFFICE.

ALPHEUS M. BLAKESLEY, OF ROCK ISLAND, ILLINOIS.

DESIGN FOR A STOVE.

SPECIFICATION forming part of Design No. 28,936, dated June 28, 1898.

Application filed April 4, 1898. Serial No. 676,470. Term of patent 3½ years.

To all whom it may concern:

Be it known that I, ALPHEUS M. BLAKESLEY, a citizen of the United States, residing at Rock Island, in the county of Rock Island and State of Illinois, have invented and produced a new and original Design for Heating-Stoves, of which the following is a specification, reference being had to the accompanying drawings, in which—

- o Figure 1 is a front elevation of the stove. Fig. 2 is a plan view of the top of the stove. Fig. 3 is a plan view of the skirt, showing also the legs.

The body of the stove A is cylindrical and 5 plain, except the corrugations near the top and bottom at $a a'$. The front of the body is largely occupied by the door D, showing 10 hinges on one side and an ordinary latch with handle on the other. The door is surrounded by a plate d, extending to the top of the stove and for an equal distance on each side of the door, ornamented with raised work in the shape of conventional scroll designs and bearing hinge-lugs and striking-lug for the door-latch. In the plate d, above the door D and 15 adjacent to the top of the stove, appears the damper E. The door D is surrounded near its outer edge with a narrow scalloped band. Within the band the upper portion is occu-

20 pied by a name-plate, on which may be inscribed the name and number of the stove, as shown. The lower part of the door is occupied by a circular damper F, with raised ornamentation radiating therefrom, producing what may be termed a "solar" design.

The base of the stove B is square in cross-section and rests on the standard b, upheld by four legs b' b''. On the front of the base appears the ash-pit door P with its handle p and having the circular dampers o o and hinges o'. Each of the dampers o is the center of a solar design similar to that on the upper door, but smaller and less elaborate. Between the dampers o is a space adapted to 25 show a name, number, or inscription descriptive of the stove. The outer edge portion of the door P is surrounded with a narrow scalloped or beaded band p', and the upper and lower portions of the base B are surrounded by similar scalloped bands b'' b''. The fire-pot or combustion-chamber of the stove is largely concealed by the skirt S, which is one of the distinguishing features of my design. This surrounds the body of the stove just

above the fire-pot and below the door D and extends downward, flaring outward somewhat in a bell shape, as shown, nearly to the plane of the top of the base B. The skirt is made of open iron-work of the same conventionalized design that is carried out in raised work on 55 the base, front, and other parts of the stove. The skirt terminates at its lower circumference in a flaring ring or flange s, as shown. The general design of the skirt is therefore a downward-projecting outward-flaring band, 60 itself composed of three separate bands or rings—viz., an upper narrow plain band, a central flaring wider band, composed of open iron-work of conventional scroll or floral designs, a lower narrow plain band flaring outward, as shown—the general contour of a radial section of the outer surface of the skirt being similar to that of a bell.

The top T is circular in horizontal cross-section, and the features shown in other parts 75 of the stove appear here arranged in concentric bands rising into a general conical form and being surmounted at the apex by an ornamental urn u, as shown.

The outer circumference of the top is occupied by a ring or flange r, which flares downward a short distance, encircling the upper part of the body of the stove B.

The top rises sharply from the ring r for the width of the narrow beaded band t. It 80 then arches upward for the greater width of the band t', ornamented with raised work, then arches again to the base of the urn, the last section v being of open-work similar to the skirt S.

Having thus described my invention, what I claim as new, and desire to secure by Letters Patent, is—

1. The design for a stove herein described and shown.
2. In the design for a stove the design for a base herein described and shown.
3. In the design for a stove the design for a skirt herein described and shown.
4. In the design for a stove the design for a top herein described and shown.
5. In the design for a stove the design of the door D herein described and shown.

ALPHEUS M. BLAKESLEY.
